(57) **CLAIM**

The ornamental design for a container with opposed dispensing ends, as shown and described.

DESCRIPTION

FIG. 1 is a perspective view of the container thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 a top plan view thereof;

FIG. 7 is a bottom plan view thereof;

FIG. 8 is a perspective view with the lids open and illustrating a spout end thereof; and,

FIG. 9 is a perspective view with the lids open and illustrating an open end thereof.

The portions shown in broken lines are included for illustrative purposes only and form no part of the claimed design.
